UNITED STATES PATENT OFFICE

EDOUARD SEIGNOL, OF PARIS, FRANCE

CARBURETOR

Application filed February 26, 1926, Serial No. 90,958, and in France April 30, 1925.

This invention relates to carburetors and more particularly to carburetors for internal combustion engines and which operate to supply fuel from a level below that of the carburetor or the engine intake, and without the intermediation of a vacuum tank and constant level reservoir.

In carburetors of the above type, especially when used on automobiles where the main fuel supply tank is situated at the rear of the car well below the level of the engine and remote therefrom, and the level of fuel in the supply tank is subject to considerable variation, the rate of fuel supply is sensitive 10 to such variation in level with resultant undesirable variation in the performance of the engine.

One of the chief objects of the present invention is the elimination of the undesirable 20 results above mentioned, by the provision of means for insuring a substantially constant fuel delivery independently of variations in the level of the fuel in the main supply tank.

Other objects of my invention will be apparent and readily understood from the following specification and the drawings accompanying the same.

The invention is illustrated by way of example in the accompanying drawings in 30 which—

Fig. 1 is a diagrammatic sectional view of a carburetor embodying the principles of my invention, and

Fig. 2 is a modification of the arrangement 35 of Fig. 1.

Referring to the drawings in detail, and first to Fig. 1, *a* is the Venturi tube of the secondary carbureting device arranged to be connected at its flanged right hand end to the 40 intake manifold of an internal combustion engine, not shown. On the engine side of the neck of the Venturi tube is provided a throttle or regulating valve *b*. A rich-mixture tube *d* of large diameter communicates 45 at its upper end with the interior of the secondary Venturi tube *a*, as shown, at a point on the engine side of the neck *c* between the neck and the throttle valve *b*, and connects at its lower end with the tube *f* situated in 50 close proximity to and slightly above the

level of the main fuel tank *e* which tank, in the case of an automobile, is situated at the rear of the car. A fuel conveying tube *g* of a small diameter extends from the neck of the primary Venturi tube *f* down into the 55 main fuel tank *e* to a point close to the bottom of the tank.

For supplying a mixture of air and fuel for running at reduced speed or idling, the relatively small pipe *h* connects the secondary 60 Venturi tube *a*, at a point on the engine side of the throttle valve *b*, with a chamber *f* surrounding the neck of the primary Venturi tube *f*, the latter being provided with small openings as shown in the drawings. The 65 chamber *f* is in communication with the tube *g* by which the fuel, or rich mixture or emulsion of fuel and air is lifted to the primary Venturi tube *f* from the main tank *e*.

The large diameter tube *d* is of sufficient 70 size to conduct a rich mixture of air and fuel in which the amount of fuel moved corresponds to that necessary for the engine. In carburetors of this general type making use of a rich mixture tube of considerable length, 75 it may occur that at the time of sudden opening of the throttle valve *b* for the purpose of accelerating the engine speed, the mixture in the tube *d* may not be sufficiently rich to insure correct carburation because of the large 80 amount of air entering the tube *a* at such time, or on the other hand the column of mixture in the tube *d* may have a very slow speed or may even be substantially still, either of which conditions results in a delivery of substanti- 85 ally all air through the secondary Venturi tube to the engine, delaying acceleration or even stalling the motor. To prevent such excessive air delivery upon sudden opening of the throttle valve, and to hasten the produc- 90 tion of the required rich mixture for acceleration, I provide the shutter *i* for the inlet end of the secondary Venturi tube *a*, pivoted on the spindle *j* and connected through crank *k* and link *l* to the rod *m* of an operating piston 95 *n*. The piston *n*, whose surface is smaller than that of the shutter *i*, is slideable in a cylinder *o*. This cylinder communicates with the manifold of the motor (not shown) through an opening in the tube *a* between the 100

throttle valve *b* and the motor. A threaded needle valve *g* serves to regulate the capacity of the passage between the cylinder *o* and the tube *a*. A small vent hole *r* is provided at the opposite end of the cylinder *o*.

To render the primary Venturi tube or carbureting device *f* self compensating for variations in the height of fuel in the main tank *e*, its fuel supply tube *g* is provided with a series of small openings *g*¹, *g*², *g*³ communicating at different levels with a tube *g*^a open to the atmosphere at its top. These small openings operate progressively to admit air into the tube *g* which air mixes with the fuel in tube *g* reducing the specific weight of the contents of the tube progressively as the level of the fuel in the tank *e* lowers past the level of the small openings. While only three points of communication are here shown between the tubes *g* and *g*^a, it is to be understood that they may be as numerous and arranged as closely together as required according to the fineness of graduation of compensation desired.

In operation, with the motor running at normal speed, the valve *b* being open, the draught of air through the secondary Venturi tube *a* keeps the shutter *i* open owing to the difference in surface area of shutter *i* and piston *n*. The latter is at this time at the outer end of the cylinder *o*. When, in order to idle, or run the motor slowly, the valve *b* is closed, the air draught or suction on the shutter *i* ceases leaving the shutter free to be actuated by the operating piston *n*. Consequently at this time the vacuum between the throttle valve *b* and the motor being very high, operates on the piston *n* to cause it to move toward the inner end (right hand end) of the cylinder *o* and move the shutter into the closed position as shown.

When, in order to accelerate the motor from slow or idling speed to normal speed, the valve *b* is opened, the vacuum in the manifold of the motor acts simultaneously on the shutter *i* and the piston *n*. Owing to the difference in surface area the shutter *i* will open, its speed of opening being retarded or slowed down by the dash-pot effect of the piston *n* and valve *g*. Thus the vacuum suddenly produced in the secondary Venturi tube *a* upon the sudden opening of the throttle *b*, instead of suddenly drawing in a great amount of external air, operates first on the tube *d* to accelerate the movement of the rich mixture therethrough, and cause an immediate increase in the action of the primary Venturi tube *f* to produce the required amount of rich mixture, without an excess of external air, after which the shutter *i* becomes completely opened. This opening of the shutter can be made to take place as slowly as desired by suitable regulation of the needle valve *g*.

During either slow or normal running of the motor, any variation in the level of the fuel in the tank *e* relative to the primary

Venturi tube *f* will be compensated for by a corresponding variation in the specific weight of the contents of the tube *g*, the mixture or emulsion of fuel and air in the tube *g* becoming leaner as the small holes *g*¹, *g*², etc., are successively permitted to communicate with the atmosphere through the lowering of the liquid fuel level, or vice versa.

It is to be noted here that while the density or richness of the mixture in tube *g* varies, the range of variation necessary for sufficient compensation is slight, the range being restricted by the smallness of the holes *g*¹, *g*², etc., so that the mixture never becomes lean enough to interfere with the operation of the motor.

In the modification of Fig. 2 the pipe for idle running, instead of being connected for taking mixture directly from the primary Venturi tube *f*, is connected to the large main supply pipe *d* near the secondary Venturi tube *a*, the pipe *d* being provided with a reduced portion *d*¹ between the Venturi tube *a* and the point where the idling tube connects in order to give at said point of connection a slight increased resistance to the passage of air.

With this arrangement, when the motor is running normally, the vacuum in *d*¹ is greater than in the idling pipe. The rich mixture produced by *f* is drawn through *d* and *d*¹ and when *b* is sufficiently opened there even occurs a slight suction through the idling pipe towards *d*¹.

When the motor runs idle, the valve *b* being closed, the degree of vacuum in the idling tube is high with the result that a partial vacuum is produced in *d* and air enters through *d*¹ into *d*, but as *d*¹ has a smaller cross section than *d* some air is also sucked through *f* lifting fuel from tank *e* to produce a rich mixture. This rich mixture further diluted by the air entering through *d*¹ produces the carbureted mixture for idle running.

The proportions of the diameters of the various pipes and tubes will obviously vary with the circumstances. By way of example, where *d* is three meters long, the proportions for the neck of *f*, tube *d*, restricted portion *d*¹, and the idling pipe, will be respectively 4, 20, 8 and 6.

What I claim is:

1. In a carbureting system, the combination with a main conduit connecting with the engine, a main fuel supply tank at a level below that of the engine and relatively distant therefrom, a primary Venturi tube located near the said tank, a secondary Venturi tube in the said main conduit, a relatively large tube connecting the outlet end of the primary venturi with the inlet end of the secondary venturi for conveying rich mixture from the primary venturi near the tank to the secondary venturi, a fuel supply tube leading

from a point below the liquid level in said tank to the said primary venturi for sucking fuel from the tank, and an air passage leading into the tank and communicating at different levels with said fuel supply tube ⁵ whereby the specific weight of the mixture of fuel and air in said fuel supply tube is varied in accordance with variations in the level of fuel in the said tank.

2. In a carburetor, the combination of a main conduit connecting with the engine, a fuel supply tank at a level below that of the engine and relatively distant from the latter; a fuel supply tube leading from said tank for sucking fuel therefrom; an air passage leading into the tank and communicating at different levels with said tube whereby the specific weight of the mixture of fuel and air in said tube is varied in accordance with variations in the level of fuel in said tank; ¹⁰ a primary Venturi tube located near the tank in communication with said fuel supply tube and relatively distant from the engine and below the level of the latter and adapted to produce a rich mixture of fuel and air; a secondary Venturi tube in the main conduit connecting to the engine; a relatively large tube for conveying rich mixture from the primary venturi near the tank into the secondary venturi in the main conduit; a relatively small tube adapted to conduct fuel for slow running directly from the said primary venturi into said main conduit at a point between the Venturi tube in said main conduit and the engine; and a throttle valve located in said main conduit between the Venturi tube therein and the point where said small tube communicates with said main conduit. ¹⁵

In testimony whereof I have affixed my signature.
